UNITED STATES PATENT O

EDWARD A. SCHREIBER, OF CHICAGO, ILLINOIS, ASSIGNOR TO EG
CHICAGO, ILLINOIS.

LOCKING DEVICE FOR STOVE-DOORS.

1.171,260.

Specification of Letters Patent. Patent

Application filed January 25, 1915. Serial No. 4,268.

To all whom it may concern:

Be it known that I, EDWARD A. SCHREIBER, a citizen of the United States, residing at Chicago, in the county of Cook and State of Illinois, have invented certain new and useful Improvements in Locking Devices for Stove-Doors, of which the following is a specification.

My invention relates to locking devices 10 for stove doors and the like and has for its object the provision of means for holding a stove door closed regardless of the various positions which the stove may assume as, for instance, in a railroad wreck, while at 15 the same time permitting the quick and easy opening of the door at will.

With the above and other objects in view, this invention consists substantially in the combination, construction and arrangement of parts all as hereinafter described, shown in the accompanying drawings, which illustrate the preferred embodiment of the invention and more particularly set forth in the subjoined claims.

25 In the drawings: Figure 1 is a front elevation of a stove door embodying my invention showing the same in its normal upright position; Fig. 2 is an end view thereof; Fig. 3 is a section with parts broken away taken on line 3—3 of Fig. 1; Figs. 4 and 5 are views in perspective of two elements forming together a locking bolt employed in my invention; Fig. 6 is a perspective view of a reversible dog employed in my invention; 30 Fig. 7 is a view of the parts shown in Fig. 2 illustrating the positions which the parts assume when the stove falls face downward; Fig. 8 is a similar view showing the door and its frame turned face upward; Fig. 9 is a similar view showing the door and its frame inverted; Fig. 10 is a partial view of my invention in perspective illustrating a locking bolt and certain of the parts associated therewith.

45 Reference numeral 20 indicates a stove door frame having the customary door opening and provided with a hinged door 21. The door carries a latch bar 22 pivoted at 23 and engaging a notched projection 24
50 formed upon the frame, in the ordinary and well known manner. A catch plate 25 is carried by the latch bar upon its rearward side and a catch 26 is pivoted to the frame 20 preferably at a point behind and below
55 the bar 22, being provided with a weight

27 below its pivot. This to engage the catch plate stove is tilted backward shifting of the pivot 28 of the catch will clear the the normal position of it closed. It will be read Fig. 3 that any movement carries the latch bar cause engagement between the catch for the reason will maintain the catch vertical.

As seen in Fig. 2, the rearward extension 29 at 30 for engagement with dog 31 having a not matically to engage the door is closed, to lock the notch of the projection swings freely upon a from the frame 20 and opening the door, it is in the position illustrated Fig. 2.

It is possible that in
sion of the stove will t
26 and the dog 31 out
ment with the latch ba
being free, therefore, t
the projection 24, mea
holding the door closed
stances. These means
tion 34 (Fig. 10) ape
formed upon the frame
the door opening; an a
ried by the door in suc
the door is closed the
registers below that of
a locking bolt general
provided with a head
freely within the apert
projection, and, prefer
its lower end in proxim
of the latch bar 22 (F
bolt has two parts, pref
shank portion 39 havin
tioned (Fig. 4), and a
40 (Fig. 5) for sliding
which is secured to th
shank. When the pa
verted position illustr
latch bar in dropping
24 may thus be caused
cent end of the bolt 37

if, for any reason the bolt sticks in its bearings.

In operation, the door 21 is closed and latched by means of bar 22 in the ordinary and well known manner. This causes automatic engagement between the extension 29 and the dog 31, resulting in the automatic locking of the latch. If the stove is so tilted as to move the catch plate 25 toward the catch 26—that is, backwardly—the nose of the dog will swing clear of the extension 29 but there will be simultaneous engagement between the plate 25 and catch 26 with the result that the latch bar 22 remains locked in the notch of the projection 24. Should the stove be thrown upon its face, as in Fig. 7, the dog 31 will hold the latch bar locked, and should it be thrown face upward, as in Fig. 8, the catch 26 will coöperate with plate 25 to keep the latch bar locked. If the stove be inverted, as in Fig. 9 and the dog and catch both disengaged from the latch bar, the bolt 37 will drop by gravity into the aperture of the projection 34, as illustrated, thus automatically locking the door closed. If, for any reason, the bolt 37 should stick in its bearings, the latch bar in dropping out of the notch of the projection 24 will strike it a sharp blow and loosen it. When it is necessary to open the door, the dog 31 is reversed into the dotted line position of Fig. 2, whereupon the latch bar 22 may be raised.

I claim:

1. The combination in a structure to be latched of a latch bar, and a pivoted weighted catch placed to clear said bar in its normal position when closed and to engage the bar to lock it in closed position when the structure is tilted backwardly.

2. The combination in a structure to be latched of a latch bar, a catch plate thereon, and a pivoted catch placed to clear said plate in the normal position of the latch bar when closed and to engage the plate to lock the closed latch bar when the structure is tilted backwardly.

3. The combination in a structure to be latched of a latch bar, a catch plate thereon, and a pivoted catch movable in a plane transverse to the plane of the latch bar and placed to clear said plate in the normal position of the latch bar when closed and to engage the plate to lock the closed latch bar when the structure is tilted backwardly.

4. The combination in a structure to be latched of a latch bar, a catch plate thereon, and a pivoted weighted catch placed to clear said plate in the normal position of the latch bar when closed and to engage the plate to lock the closed latch bar when the structure is tilted backwardly.

5. The combination in a structure to be latched of a latch bar, a catch plate thereon, and a swinging, weighted catch placed to clear said plate in the normal position of

the latch bar when closed and to engage the plate to lock the closed latch bar when the structure is tilted backwardly.

6. The combination in a structure to be latched of a latch bar, a catch plate upon the rearward side thereof, and a weighted catch pivoted at a point below and rearwardly of said plate and formed to clear said plate in the normal position of the latch bar when closed and to engage the plate to lock the closed latch bar when the structure is tilted backwardly.

7. In a stove, the combination with a door frame and a door therefor, of a pivoted latch carried by the door, a catch plate carried upon the rearward side of said latch bar, a pivot pin upon said frame positioned below and rearwardly of the latch plate, and a weighted catch mounted upon said pivot pin and formed to clear said plate in the normal position of the latch bar when closed and to engage said plate to lock the latch bar when the stove is tilted backwardly.

8. The combination in a structure to be latched of a latch bar, a reversible locking dog movable in a plane transverse to the plane of the latch bar, which automatically locks the latch bar when the bar is closed and the structure is in its normal position, a catch plate upon the latch bar, and a pivoted catch placed to clear said plate in the normal position of the latch bar when closed and to engage the plate to lock the closed latch bar when the structure is tilted backwardly.

9. The combination in a structure to be latched of a latch bar, a reversible locking dog adapted normally to automatically lock the latch bar in closed position and to release the latch bar when said structure is tilted backwardly, a catch plate upon said bar, and a pivoted catch placed to clear said plate in the normal position of the latch bar when closed, and to engage the plate to lock the closed latch bar when the structure is tilted backwardly.

10. The combination in a structure to be latched of a latch bar formed with a notch, a pivoted reversible locking dog having a nose adapted to engage said notch automatically, when the bar is closed, to lock the latch bar, and positioned to release the latch bar when said structure is tilted backwardly, a catch plate formed upon the rear side of the latch bar, and a weighted catch pivoted rearwardly of the latch bar and placed to clear said plate when said dog is in locking engagement with the bar and to engage said plate to lock the bar in closed position when said dog releases the bar.

11. In a stove, the combination of a door frame; a door mounted thereon; automatic means for holding the door closed regardless of the position of the stove, comprising a pivoted latch bar upon the door, a notched

stud upon the frame for engagement by the latch, a pivoted dog movable in a plane transverse to the plane of the latch bar and adapted to lock the latch bar in closed position when the stove is upright or tilted forwardly on its base, a catch pivoted upon the frame movable in a plane transverse to that of the latch bar and formed to clear the latch bar when said dog is in locking position and to engage the latch bar to lock it when said stove is tilted backwardly, an apertured projection upon said frame adjacent the door opening thereof, a lug upon the door having an aperture registering below the aperture of said projection during the closed position of the door, and a bolt carried by said lug and slideable by gravity into the aperture of said projection when said stove is inverted.

12. In a stove, the combination of a door frame; a door mounted thereon; and automatic means for holding the door closed regardless of the position of said stove, comprising a pivoted latch bar upon the door, a notched stud upon the frame for engagement by the latch, a pivoted dog movable in the plane transverse to the plane of the latch bar and adapted to lock the latch bar in closed position when the stove is upright or tilted forwardly on its base, a catch pivoted upon the frame movable in a plane transverse to that of the latch bar and formed to clear the latch bar when said dog is in locking position and to engage the latch bar to lock it when said stove is tilted backwardly, an apertured projection upon said frame adjacent the door opening thereof, a lug upon the door having an aperture registering below the aperture of said projection during the closed position of the door, and a bolt carried by said lug and slideable by gravity into the aperture of said projection when the said stove is inverted, said bolt being so positioned as to be struck by the latch bar.

13. The combination with a door frame of a door mounted thereon, a pivoted latch bar for the door, and gravity operated means for holding the door closed when it is inverted comprising a sliding bolt; said latch bar being placed to strike said bolt when the door is inverted.

14. In a stove, the combination with a door and door frame, of a latch bar pivoted to the door and adapted to engage the door frame, an element on the frame above the latch bar, when the door is closed, which operates by gravity to hold the latch bar in engagement with the frame, when the stove is in normal position, a perforated lug at the upper edge of the door, a lug on the

upper edge of the frame having an aperture which registers with the perforation in the lug on the door, when the door is closed, and a bolt slideable in the lug on the door, the lower end of which is provided with a weight adapted to move the bolt into the aperture in the lug on the frame when the stove is inverted.

15. In a stove, the combination with a door and door frame, of a latch bar pivoted to the door and adapted to engage the door frame, an element on the frame above the latch bar, when the door is closed, which operates by gravity to hold the latch bar in engagement with the frame, when the stove is in normal position, a perforated lug at the upper edge of the door, a lug on the upper edge of the frame having an aperture which registers with the perforation in the lug on the door, when the door is closed, a bolt slideable in the lug on the door, the lower end of which is provided with a weight adapted to move the bolt into the aperture in the lug on the frame when the stove is inverted, and a pivoted latch on the frame back of the latch bar, when the door is closed, which normally stands out of the path of the latch bar but engages the same when the stove is tipped backwardly.

16. In a stove, the combination with a door and door frame provided with a latch mechanism effective by the weight of its parts to hold the door in engagement with the frame when the stove is in its normal position, of a perforated lug at the upper edge of the door, a lug on the upper part of the frame having an aperture which registers with the perforation in said lug, when the door is closed, a bolt slideably arranged in the lug on the door, and a weight on the end of said bolt adapted to move the bolt into the aperture in the lug on the frame in case the stove is inverted.

17. In a stove, the combination with a door and a door frame provided with a latch mechanism effective by the weight of its parts to hold the door in engagement with the door frame when the stove is in its normal position, of a bolt mounted on the door at its upper edge, the upper end of which is out of contact with the door frame when the stove is in its normal position, said bolt being weighted, freely slideable upon the door, and adapted, when the stove is inverted, to fall by gravity into locking engagement with the door frame.
